UNITED STATES PATENT OFFICE

JEAN BAPTISTE EMILE ERNEST ARNOULT, OF PARIS, FRANCE, ASSIGNOR TO ETABLISSEMENTS ERNEST ARNOULT, OF PARIS, FRANCE

HEAT EXCHANGER

Application filed April 5, 1929, Serial No. 352,813, and in France April 23, 1928.

The object of the present invention is a thermic exchanger, allowing the caloric or frigorific energy of one fluid to pass over to another fluid in a continuous manner, by means of the interposition of a ceramic, metallic, mixed or other sort of partition; the said exchanger being particularly characterized by the fact that the channels, in which the fluids circulate, are arranged in such a way that all the partitions are substantially in contact with the two fluids, thus reducing the weight and encumbrance of the apparatus to a minimum for the same exchanging capacity.

According to another particularity of the invention, the whole apparatus is built up by placing side by side alternately two types of piling up elements, conveniently lodged in interlocking relation so as to constitute alternatively in the succeeding pilings rectangularly directed conducts, intended respectively for the circulation of the one or the other fluid.

Other characteristics will result from the following description:

In the annexed drawing, which is given merely by way of example:

Figure 1 is a vertical longitudinal section on the line 1—1 in Figure 2 of one exchanger, according to the invention.

Figure 2 is a vertical transversal section on the line 2—2 of Figure 3.

Figure 3 is a horizontal section on the line 3—3 of Figure 1.

Figure 4 is a horizontal section on the line 4—4 of Figure 2.

Figure 5 is an elevational view of a constitutive element of the first type of pilings.

Figure 6 is the corresponding plan view.

Figure 7 is a vertical section on the line 7—7 of Figure 6.

Figure 8 is an elevational view of a second element cooperating with the preceding in the formation of the first pilings.

Figure 9 is the corresponding plan view.

Figure 10 is the vertical section on the line 10—10 of Figure 9.

Figure 11 is the elevational view of a constitutive element of the second type of pilings.

Figure 12 is a horizontal section on the line 12—12 of Figure 11.

Figure 13 is a vertical section on the line 13—13 of Figure 11.

According to the present illustration, the exchanger, supposed to be made of ceramic or similar material, is especially intended to recover the heat carried away by fumes, the recovery being profited by the air intended to burn the gas used when heating a furnace to which the exchanger is annexed.

The fumes arrive for instance at A and escape at B, after passing as per arrow fully traced through the horizontal channels C. The horizontal and vertical baffle plates D and E allow to increase considerably the travel of the fumes.

The cold air, which is to be heated, arrives from below in F and raises as per dotted arrows into the conduits G and passes out into the upper collector H from which the warm air issues by the conduit I.

It will be seen from this that the recovery is methodical, since the fumes travel in an opposite direction to the air that is being heated.

According to one of the features of this invention, the elements that constitute the conduits C and G are such that all their partitions are in contact with the two fluids.

In this particular instance, this result is obtained by placing side by side two types of pilings J₁ J₂ shown especially in Figure 2.

The pilings J₁ are obtained by the superposition of rows, which are formed alternatively by placing side by side the elements K and L. The elements K (Figures 2—5—6—7) have a vertical U-shaped section, transversal to the pilings J₁ (Fig. 5). The elements L (Figures 2—8—9—10) have a vertical T-shaped section transversal to the pilings J₁ (Figure 10) and a U-shaped vertical section parallel to the piling J₁ (Figure 8).

The pilings J₂ are constituted by the superposition of identic rows formed by placing side by side elements M (Figures 2—11—12—13), of vertical T-shaped section, perpendicular to the pilings J₂ (Figure 13) and of horizontal section in form of a double T.

The lateral wings m of said elements M extend between two consecutive U -shaped members K .

The exchanger is, of course, completed by 5 any other elements of current or special shapes intended for making baffles and channels near the walls.

Furthermore, in the case of ceramic partitions, these are disposed in such a way as to 10 allow the free expansion of all their parts, so as to avoid their rupture and to prevent the mixture of the two fluids, the joints being, for this same purpose, conveniently crossed and provided with suitably placed jointings, 15 thus allowing a construction composed of several materials of different nature.

The invention is not limited to the embodiments shown and described, which have merely been chosen as an example. It has 20 been supposed that the pilings were vertical, but it is quite evident that the invention applies to exchangers in which the pilings J_1 and J_2 , or similar, might be replaced by superposed layers.

25 Having now described my invention what I claim as new and desire to secure by Letters Patent is:

1. In a heat exchanger a number of aligned spaced longitudinal conduits for a first fluid, 30 spacing members between each two consecutive conduits, and partitions on either side of said aligned conduits and separated from said conduits, whereby transversal conduits are formed for a second fluid between each partition and the aligned longitudinal conduits.

2. In a heat exchanger a number of aligned spaced longitudinal conduits for a first fluid, 40 spacing members between each two consecutive conduits, and partitions on either side of said aligned conduits, separated from said conduits and provided with ribs extending between each two consecutive longitudinal conduits, whereby transversal conduits are formed for a second fluid between each partition and the aligned longitudinal conduits.

3. In a heat exchanger a number of aligned 45 U -shaped spaced members, a T -shaped member between each two consecutive U -shaped members and adapted to close the open side of one of said U -shaped members and to bear against the middle web of the other U -shaped member, whereby longitudinal conduits are formed by the hollow spaces in each U -shaped member for a first fluid, and partitions on either side of said aligned members provided with ribs extending between each two consecutive U -shaped members in the spaces left free between the wings of the T -shaped members, whereby transversal conduits are formed for a second fluid between each partition and the aligned U -shaped members.

65 4. In a heat exchanger a number of rows

of aligned U -shaped spaced members, a T -shaped member between each two consecutive U -shaped members and adapted to close the open side of one of said U -shaped members and to bear against the middle web of the other U -shaped member, whereby longitudinal conduits are formed by the hollow spaces in each U -shaped member for a first fluid and partitions between each two consecutive rows of aligned U -shaped members provided with ribs extending between each two consecutive U -shaped members in the spaces left free between the wings of the T -shaped members, whereby transversal conduits are formed for a second fluid between each partition and each row of aligned U -shaped members.

5. In a heat exchanger a number of rows of aligned U -shaped spaced members, a T -shaped member between each two consecutive U -shaped members and adapted to close the open side of one of said U -shaped members and to bear against the middle web of the other U -shaped member whereby longitudinal conduits are formed by the hollow spaces in each U -shaped member for a first fluid, and aligned adjacent T -shaped partitions between each two consecutive rows of aligned U -shaped members having their lateral wings extending between each two consecutive U -shaped members in the spaces left free between the wings of the T -shaped members, whereby transversal conduits are formed for a second fluid between the T -shaped partitions and the U -shaped members.

In testimony whereof I have signed my name of this specification.

JEAN BAPTISTE EMILE ERNEST ARNOULT.
